TERMITE CONTROL

Allan P. Bloxsom, Houston, Tex.

Application August 28, 1937, Serial No. 161,423

3 Claims. (Cl. 72—77)

This invention relates to a method and means for the control of termites or other insects by the use of an insect repellant in concrete forming the supporting structure for a building and in so constructing such support as to render the use of a repellant of maximum effect.

The primary object of the invention is to effect a control of termites by adding to the foundation concrete while in a plastic stage an insecticide that does not materially alter the strength of such foundation material.

Another object is to provide a supporting structure for a building, such structure including an insecticide, homogeneously incorporated therein, the foundation being so constructed as to provide mechanical barriers which also serve to form repellent retaining pockets.

Another object is to provide a termite control foundation having pockets in the surfaces thereof, such pockets being of such configuration as to effectively entrap insect repellent gases.

Still another object is to provide a building foundation having facial pockets which are so oriented as to retain insect repellants which may be gaseous or solid.

It is also an object to provide a novel liner for a concrete form, such liner being so constructed as to produce facial pockets in the structural member cast in the form.

Other objects, together with the foregoing, will be apparent from the following description taken in connection with the drawing in which:

Fig. 1 is a sectional view showing a foundation and superposed floor structure embodying the invention.

Fig. 2 is a sectional view similar to that shown in Fig. 1, but illustrating a modified form of repellent entrapping pockets in the surface of the foundation structure.

Fig. 3 is a sectional view of a foundation showing the manner of using the pocket forming mat or liner comprising an element of the invention.

Fig. 4 is a view similar to that shown in Fig. 3 but showing a modified form of mat giving rise to rectangular pockets in the surfaces of the foundation.

Fig. 5 is an elevation of a portion of a foundation formed in accordance with the embodiment shown in Fig. 4.

Figs. 6 and 7 are views of modified forms of pocket forming mats used in a manner similar to that illustrated in Figs. 3 and 4.

Various methods and means have heretofore been proposed for the control of the migration

of destructive insects upwardly on building supports to the superposed structure to which material damage is effected by such insects. The use of destructive chemicals and mechanical barriers have been proposed but such practices have met only with a limited degree of success.

The present invention comprehends a novel use of repellent chemicals and also the use of such chemicals in combination with mechanical barriers which serve the dual function of retarding the migration of insects over the surface of a foundation and also entrapping a repellent which is destructive to insects during migration.

The present invention in its broadest aspect resides in constructing the foundation of building structures of a hydraulic cement such as Portland cement, to which has been added an insect repellent such, for example, as any of the varieties of cresylic acid. The use of such chemical here mentioned is illustrative only, as other phenolithic products or other chemicals such as arsenious compounds or cuprous compounds may be utilized without departing from the spirit of the invention, so long as the substance used will be destructive or a repellent for the insects.

In accordance with the invention, the chemical as above mentioned is homogeneously distributed throughout the body of the foundation of material and by virtue of such distribution provides a repellent in the surface layers of the foundation and also through the minute voids in the foundation material gives rise to slow exudation of gases over a long period of time. Such gases are destructive to insect life and in this manner the objects of the invention are realized.

The repellent chemical is added to the concrete while the concrete is in the plastic stage. Such chemical may be added in any suitable manner, but is preferably added in solution in water of any suitable concentration up to supersaturation. A concentration of cresylic acid up to seven per cent has been found to alter the tensile strength of concrete less than ten per cent after setting for one week, while a concentration of from three to five per cent does not alter the final tensile strength to any appreciable extent. Such concentrations of the repellent are sufficient to produce desired results and it is obvious from the foregoing that these concentrations may be used without materially affecting the strength of the concrete.

In Fig. 1 is shown a construction embodying the invention wherein 1 is the side supporting wall in section, such wall being provided with

5 facial grooves 2 to serve as barriers and also to entrap gases which exude from the body of the wall 1. End wall 3 is provided with similar grooves 4 to serve the same purpose as do the 10 grooves of the side wall. It should be noted that an offset is provided in the grooves at 5 in order to minimize the weakening effects of the groove and also to form pockets for retaining the exuded gases.

10 At 6 is shown a floor structure resting upon the walls 1 and 3 and provided with grooves or pockets 7 for the entrapment of gases.

15 In Fig. 2 is shown a modified form of the invention shown in Fig. 1, similar parts being identified by primed reference characters. It should be noted, however, that the grooves 2' are upwardly inclined instead of downwardly inclined as shown in Fig. 1. The construction shown in Fig. 1 is designed for use where gas exuding from 20 within the concrete is lighter than air and hence tends to rise but is entrapped in the downwardly facing pockets formed by the grooves. On the other hand, the construction shown in Fig. 2 is designed for use where the exuding gas is heavier 25 than air and hence tends to move downwardly but is entrapped within upwardly opening pockets.

30 In Fig. 3 is shown the manner of construction of the foundation as shown in Fig. 1. In accordance with this phase of the invention the usual form 10 is provided with a liner or mat of rubber or other suitable material having ridges 12. The material of the mat 10 is of sufficient 35 rigidity to maintain its form and hence to form grooves 2 on the faces of the concrete foundation. It is apparent that this mat may be readily removed from the surface of the concrete when the form 10 is removed and hence may be repeatedly used whereby the expense incident to practice of the invention is minimized.

40 In Fig. 4 is shown a modification of the embodiment shown in Fig. 3, such modification comprising a mat having rectangular ridges; such ridges, as is the case with the modification shown 45 in Fig. 3, are not continuous, the discontinuities being staggered to form a surface having staggered pockets as shown at 13 in the elevational view of the wall shown in Fig. 5. It is believed apparent that such construction does not materially 50 reduce the strength of the foundation structure but that the pockets formed therein serve as gas retaining pockets and that the surface so provided serves as a barrier to the migration of insects thereover.

55 Figs. 6 and 7 illustrate modified types of liners to be used in practicing the invention. The form

5 shown in Fig. 6 is provided with cylindrical projections 14 while the form shown in Fig. 7 is provided with hexagonal projections 15, whereby complementary pockets are formed in the surface of the foundation structure. It is to be understood that the mats used for forming pockets in the surface of the foundation may be so constructed as to provide gas retaining pockets which open diagonally upwardly or downwardly as pointed out in connection with Figs. 1 and 2. 10

15 In accordance with the foregoing, it is apparent that the present invention provides a novel method and means for controlling the migration of destructive insects to building structures.

While specific examples have been presented 20 to illustrate the preferred embodiments and improvements, the invention is not confined thereto but is limited only by the prior art and appended claims.

25 It is to be understood, for example, that in addition to the use of a suitable chemical in the concrete forming the foundation 1, the pockets therein which serve to entrap exuded gases and which also act as barriers to the migration of destructive insects may be partially or entirely 30 filled with insect repellent of high concentration at any time. Likewise, while the preferred embodiment and disclosed modifications show the provisions of facial pockets on both sides of the support elements, it is to be understood that the 35 facial pockets may be provided on one side only of a support element if such construction be deemed desirable or necessary. It is therefore intended that the invention shall include such practices. 35

What is claimed as new is:

1. An insect controlling foundation comprising support members of an intimate mixture of hydraulic cement and a volatile insect repellent, and pockets in the surface of said foundation 40 adapted to entrap gases from said repellent whereby the migration of insects over the surface of said support members is prevented.

2. An insect controlling foundation comprising support members of an intimate mixture of hydraulic cement and a volatile insect repellent, and upwardly opening pockets in the surface of 45 said members to entrap repellent gases that are heavier than air.

3. An insect controlling foundation comprising support members of an intimate mixture of hydraulic cement and a volatile insect repellent and downwardly opening pockets in the surface of 50 said members to entrap light repellent gases therein.

55 ALLAN P. BLOXSOM.
